UNITED STATES PATENT OFFICE.

ALBERT L. BARON, OF NEW YORK, N. Y.

DESIGN FOR A LAMP-BASE.

SPECIFICATION forming part of Design No. 29,173, dated August 9, 1898.

Application filed June 18, 1898. Serial No. 683,862. Term of patent 3½ years.

To all whom it may concern:

Be it known that I, ALBERT L. BARON, a citizen of the United States, residing in New York, borough of Brooklyn, State of New York, have invented a certain new and original Design for a Base for Lamps, of which the following is a specification.

The design consists of a lamp-base, as shown in the accompanying drawings—that is to say, it has a cylindrical body flat upon one end and conical at the other end. The cylindrical portion A, which is formed with a rim-flange *a*, represents the shell portion of a cartridge for ordnance, and the tapering or conical end B represents the projectile, *b* being the line of division between the shell and the exposed part of the projectile.

The base is supported upon feet or legs formed to represent crossing cannons, C representing the cannons and *c* the trunnions thereof. The shell lies in the crotch above the crossed ends of the cannon.

D are small spheres representing cannon-balls appearing at the bottom part of the shell adjacent to the cannons.

25

The cylindrical part A contrasts in color with the part B, *b* being the dividing-line.

E is a circular hub or boss upon the upper side of the cylindrical part A.

The essential feature of the design is the 30 base, having the cylindrical part A and the conical part B and a line of division *b* between the two parts, the base being supported upon legs representing crossed cannons.

35

I claim—
The design for a lamp-base herein shown and described.

In testimony whereof I have hereunto subscribed my name.

ALBERT L. BARON.
